UNITED STATES PATENT OFFICE.

HERBERT G. BEEDE, OF PAWTUCKET, RHODE ISLAND.

GARMENT-PRESSING MACHINE.

Application filed January 11, 1927. Serial No. 160,369.

This invention relates to a garment pressing machine adapted to be used in tailoring, dry cleaning, laundrying, clothing manufacturing and other establishments for steaming, sterilizing, shaping and drying garments in practically one operation or setting, and refers more particularly to the actuating and controlling means for the movable pressing element.

10 In machines of this character the upper pressing element, commonly known as the head, is hinged upon the main supporting frame to swing vertically about an axis parallel with and some distance to the rear of the longitudinal center of the lower pressing element or buck and is preferably operated by a pedal lever through the medium of one or more toggles.

The main object of the present invention is 20 to provide a simplified leverage system in which the forces applied to flex the toggles in reverse directions for operating the press-head to and from its pressing position are more nearly in the direction of flexion of the 25 toggle joints and, therefore, more normal to a direct line between the toggle pivots in all positions of adjustment thus permitting the press-head to be brought to its pressing position with greater ease and greater pressure 30 and with less power applied to the pedal lever than has heretofore been practised.

Another object is to provide an adjustable 35 resilient connection between the main toggle and press head to compensate for varying degrees of closing movement upon work of different thicknesses in which a relatively high degree of yielding resistance may be obtained through a comparatively light spring wholly at one side of the toggle.

40 Other objects and uses relating to specific parts of the machine will be brought out in the following description.

In the drawings:—

Figure 1 is a side elevation, partly in section, of a garment pressing machine embodying the various features of the invention.

Figure 2 is a horizontal sectional view through the rear end of the head supporting arm taken on the plane of line 2—2, Figure 1.

As illustrated, this machine comprises a main supporting frame —1— of any suitable form, size or material adapted to rest upon a floor or other foundation for receiving and 55 supporting cooperative pressing elements —2— and —3— together with other parts of

the machine in operative position most convenient for carrying out the objects stated.

The upper pressing element —3— is mounted upon the front end of a vertically 60 movable rock arm or lever —4— of the first-kind which is fulcrumed or pivoted intermediate its ends at —5— to an upwardly extending bracket —6— on the rear portion of the frame —1— to swing about a horizontal 65 axis parallel with and some distance to the rear of the longitudinal center of the buck —2— for moving the press head into and out of pressing co-action with the buck, said bracket —6— and fulcrum —5— being disposed some distance to the rear of the buck 70 to leave ample space for the manipulation of the garments around and upon the buck preparatory to pressing.

The rear end of the head-supporting arm 75 —4— is provided with a reduced extension —11— having parallel sides for receiving a counter-weight —7— which is placed over and upon the extension and held in operative position by a removable key —12— and is recessed in its underside and front end for receiving portions of the yielding connections between the rear toggle and head-supporting arm —4—.

The extension —11— is also provided with 80 a vertical opening therethrough and a lengthwise slot therein for receiving portions of the connections between the rear toggle lever and head-supporting arm as will be hereinafter more fully explained.

Head operating means.

The head supporting arm —4— and its press head —3— are operated and controlled by a system of toggle levers and links arranged in such manner that the force applied to each toggle is substantially normal or at right angles to a direct line between the fulcrum of the toggle lever and toggle joint and approximately normal to a direct line between the fulcrum and point of connection of the toggle lever with the member to which the power is to be applied whereby the press head may be moved to and from its pressing position with greater ease and rapidity of motion and with less power than has heretofore been practised.

As illustrated, this leverage system comprises a pedal lever —13— operatively connected by a link —14— to one of the arms of a bell-crank lever —15— having its other arm connected by a link —16— to a main

toggle lever —17— which, in turn, is operatively connected to the rear end extension —11— of the head-supporting arm —4—.

The pedal lever —14— extends forwardly and rearwardly near the base of the frame —1— and is pivotally fulcrumed at its rear end at —18— to said frame, the front end of the pedal-lever being extended forwardly beyond the front portion of the frame and 10 provided with a pedal —19— by which it may be depressed.

The link —14— is pivoted at its lower end at —20— to the intermediate portion of the 15 pedal lever —19— and has its upper end pivotally connected at —21— to the shorter arm of the bell-crank lever —15—, said link being of the turn-buckle type for relative adjustment of the levers —13— and —15—.

The bell-crank lever —15— is pivotally 20 fulcrumed at —22— to the frame —1— in a plane between the pedal lever —13— and table —10— to extend forwardly and rearwardly from its fulcrum, the rear arm of the lever being relatively long and pivotally 25 connected at —23— to the link —16— which, in turn, is pivotally connected at —24— to the intermediate portion of the lever —17—.

The rear end of the bell-crank lever —15— 30 is provided with an extra weight —25— and together with the link —16— constitutes what may be termed the intermediate toggle connection between the main toggle lever —17— and link —14—.

The main or rear toggle lever —17— is 35 pivotally fulcrumed at its lower end at —26— to the base of the frame —1— just at the rear end of the pedal lever —19— to extend upwardly toward the head-supporting arm —4— and has its upper end pivotally connected at —27— to the lower end of an upwardly extending toggle member —28— which is preferably composed of sections —29— and —30— having threaded engagement with each other for relative endwise adjustment, the lower section —29— being directly connected to the upper end of the lever —17— through the medium of the pivot —27—.

The upper section —30— is shouldered 40 against the lower end of and extends through an opening in a yoke member —31— which is eccentrically pivoted at —32— to the intermediate portion of a relatively short lever —33—.

This lever —33— is pivotally fulcrumed 45 at its front end at —34— to and between opposite walls of the lengthwise slot in the rear end extension —11— of the head supporting arm —4— to rock vertically in said slot.

The rear end of the lever —33— is provided 50 with a vertical opening —35— for receiving the upper end of a bolt or rod —36— which is pivoted at —37— to and be-

tween the opposite walls of the opening —35— to extend downwardly therefrom through an opening —38— in the lower rear end of the extension —11— as shown in Fig. 1.

A coiled spring —39— surrounds the intermediate portion of the bolt —36— and has its upper end seated against the underside of the extension —11— and its lower end engaged with an adjustable seat —40— 75 which is held in operative position by an adjusting nut —41—.

The yoke member —31— extends through and is pivoted to opposite walls of a slot —42— in the intermediate portion of the 80 lever —33— which, as previously stated, is movable in the lengthwise slot in the extension —11— so that the opposite walls of the last-named slot may serve to hold the pivotal pins —32— and —37— against endwise displacement as shown more clearly in Figure 2.

A hand wheel —43— is secured to the upper end of the section —30— to engage the upper end of the yoke member —31— to 90 cooperate with the shouldered portion of the section —30— in holding said section and the yoke member —31— against relative endwise movement.

The hub of the hand wheel —43— is provided 95 with corrugations or notches —44— adapted to be engaged by a spring actuated detent —45— for holding the hand wheel —43— and section —30— against accidental turning movement.

The intermediate portion of the pedal lever —13— and upper end of the toggle lever —17— are connected by one or more 105 retracting springs —46— tending to flex the toggle joint —27— inwardly and also to elevate the pedal lever for returning the press head to its open position when the latter is released from its pressing position or when pressure is removed from the pedal —19—.

The object of the axially adjustable toggle member —28— is to permit adjustment 110 of the press head —3— relatively to the buck —2— according to the thickness of the material operated upon and also to adjust the toggle joint —27— so as to prevent excessive rearward flexion of the toggle to a straightened locking position or rather to assure a slight inward flexure of the joint beyond a direct line between the opposite ends of the toggle when the press head is brought to its pressing position and thereby to facilitate the free return of said pressing head to its open position by the retracting spring or springs —46—.

The object of the compensating lever —33— and spring —39— is to establish a resilient connection between the rear toggle and head-supporting arm —4— and thereby to compensate for varying thicknesses of 120

material operated upon between the pressing elements by the use of a comparatively light spring as —39— without sacrificing the degree of pressure required for shaping the 5 garment and also to reduce the shock and noise incidental to the closing of the press head upon the work.

It will be observed that the toggle lever —17— and rear arm of the bell-crank lever 10 —15— are arranged to swing in approximately the same general direction when operated to open or close the press head and that the pivots —23— and —24— travel in arcs between the fulcrums —22— and —26— 15 of the levers —15— and —17— respectively and that the pivotal joint —23— between the lever —15— and link —16— is movable to opposite sides of a direct line between said fulcrums, the object of which is to keep 20 the link —16— in a position substantially normal or at right angles to the lever —17— in all positions of adjustment or at least in the extreme positions of adjustment so as to enable the press head to be forced to and 25 from its pressing position with greater ease and with less power applied to the pedal —19— than has heretofore been practised.

It will also be observed that the link 30 —14— is connected to the pedal lever —19— in such manner as to maintain a position substantially tangential to the arc of movement of its pivotal connection —21— with the bell-crank lever —15— or approximately normal to a direct line between the fulcrum —22— and toggle joint —23— of the bell-crank lever particularly when adjusted to bring the press head to its pressing position at which time the force applied to the toggle lever —17— by the toggle lever 40 —15— through the medium of the link —16— will also be substantially normal to a direct line between the fulcrum —26— and toggle joint —27— of the lever —17—, all of which contributes materially to the 45 rapidity and ease of operation and power of application of the press head to the work.

The toggle lever —15— is adjusted by means of the adjustable link —14— so as to prevent straightening of the toggle joint 50 —23— when the press head is closed thus permitting quick and free return of the press head to its open position when pressure upon the pedal —19— is released.

Operation.

When the press head is forced to its pressing position as shown by full lines in Figure 1 the rear toggle —17— and intermediate toggle —15— will be moved toward their 60 straightened positions, which movement will be limited by the engagement of the press head with the work upon the buck but in case the thickness of the work should vary slightly this variation will be compensated by the upward rocking movement of the

compensating lever —33— against the action of its retracting spring —39— for the reason that when the closing movement of the press head is limited by the engagement with the work on the buck the upward thrust of the 70 rear toggle on the yoke member —31— will rock the rear end of the lever —33— upwardly about its fulcrum —34— against the action of the spring —39— which may be comparatively light owing to the relatively short distance between the pivots —32— and —34— as compared with the distance between the fulcrum —34— and pivotal connection —37— between the lever —33— and bolt —36—, it being understood that this 75 bolt is slidably freely in the opening —38— in the underlying portion of the extension —11—.

In adjusting the press head to the work and also in adjusting the toggle joint —27— 80 to prevent straightening of the toggle it is simply necessary to withdraw the detent —45— from engagement with the hand wheel —43— thus permitting the latter to be turned in one direction or the other for 85 adjusting the section —30— endwise relatively to the section —29— for varying the distance between the pivots —27— and —32—.

In like manner the distance between the 90 pivots —20— and —21— may be varied by the axial adjustment of the link —14— for preventing the straightening of the toggle joint —23— between the members —15— and —16—.

When pressure upon the pedal —19— is released the spring —46— aided by the weight —7— will automatically restore the movable parts to the positions shown by dotted lines or until the opening movement 100 of the press head is limited by the engagement of its supporting arm —4— with the yielding buffer —8—.

It will also be noted that the extra weight 105 —25— on the lever —15— may assist in restoring the movable parts to their dotted positions.

It will be noted that by connecting the spring —46— diagonally across the levers —13— and —17— enables the toggle joint 115 of the lever —17— to be flexed inwardly and at the same time assures a restoration of the pedal lever —13— to its elevated position thereby obviating the use of separate springs for these different operations.

When closing the press head the momentum imparted to the weight —25— acting through the link —16— upon the toggle lever —17— produces a more or less hammer blow of the press head upon the work at the 125 final closing and also assures the locking of the pedal lever in its pressing position when a locking member is used.

What I claim is:—

1. In a garment pressing machine having 130

- 5 a frame and a movable pressing element, a toggle having one of its members fulcrumed on the frame and its other member operatively connected to said element, and pedal-operated means for applying force to said one member in the direction of flexion of the toggle joint and substantially normal to a direct line between said joint and frame-fulcrum of the said one member in both 10 extreme positions of adjustment.
2. In a garment pressing machine having a frame and a movable pressing element, actuating means for said element including a pedal-lever, a toggle having one of its members fulcrumed on the frame and its other member operatively connected to said element, and means actuated by the pedal-lever for applying force to one of the toggle members in the direction of flexion of the 15 toggle joint and substantially normal to a direct line between the ends of the said one toggle member.
3. In a garment pressing machine having a frame and a movable pressing element, a toggle having one of its members fulcrumed on the frame and its other member operatively connected to said element, a pedal-lever fulcrumed on the frame adjacent the first-named fulcrum, and means actuated by 20 the pedal lever for applying force to the toggle in the direction of flexion of the toggle joint and substantially normal to a direct line between the frame-fulcrum of the said one toggle member and the toggle joint.
4. In a garment pressing machine having a frame and a movable pressing element, a toggle having one of its members connected to the movable element and its other member constituting a lever fulcrumed in the frame, and pedal-operated means for applying force to said toggle-lever in the direction of flexion of the toggle joint and substantially normal to a direct line between the toggle joint and frame-fulcrum of the lever in all positions of adjustment of said lever.
5. In a garment pressing machine having a frame and a movable pressing element, a toggle having a toggle link fulcrumed on the frame and operatively connected to said element, an additional toggle having a toggle link fulcrumed on the frame and operatively connected to the first-named toggle link and having the flexing joint of the additional toggle movable to opposite sides of a direct line between the fulcrums of both toggle links, the connection between said toggle links being arranged to maintain a 50 position substantially normal to a direct line between the fulcrum and toggle-joint of the first-named toggle link and a pedal-lever for actuating the additional toggle link.
6. In a garment pressing machine having a frame and a movable pressing element, a toggle having a toggle link fulcrumed on the frame and operatively connected to said element, a pedal lever, a bell-crank lever, a link pivotally connected to both levers to move endwise approximately tangential to the arc 70 of movement of its point of connection with the bell-crank lever in all positions of adjustment, and means actuated by the bell-crank lever for applying motive force to the toggle link in a direction substantially normal to a direct line between the frame-fulcrum of the toggle link and joint of the toggle.
7. In a garment pressing machine having a frame and a movable pressing element, a toggle having a toggle link fulcrumed on the frame and operatively connected to said element, an additional toggle having one of its members constituting a bell-crank lever fulcrumed on the frame and its other member pivotally connected to said toggle-link between the fulcrum of said link and flexing joint of the first-named toggle and arranged to maintain a position at substantially right angles to a direct line between the fulcrum of said link and the joint of the first-named toggle in all positions of adjustment, a pedal lever, and a link pivotally connected to the pedal lever, and to said bell-crank lever and arranged to maintain a position approximately tangential to the arc 80 of movement of its point of connection with the bell-crank lever.
8. A garment pressing machine as in claim 5 in which extra weight is applied to one of the members of the additional toggle near its flexing joint to assist in flexing said joint away from a direct line between the fulcrum and point of connection of the additional toggle with the first-named toggle 90 when the movable pressing element is released from its pressing position.
9. A garment pressing machine as in claim 5 in which the pedal lever and toggle lever are yieldingly connected to each other by a retracting spring extending across the second-named toggle to move to opposite sides of the flexing joint of the latter as the pressing element is moved to and from its 100 pressing position.
10. In a garment pressing machine having a movable pressing element, a lever fulcrumed on said element, resilient connections between said lever and element, and means operatively connected to said lever 105 for operating the pressing element.
11. In a garment pressing machine having a movable pressing element, a lever fulcrumed near one end upon said element, resilient connections between the other end of the lever and element, and means operatively connected to the intermediate portion of said lever for operating the movable element.
12. In a garment pressing machine having 115
- 130

a movable pressing element, a lever fulcrumed near one end upon said element, resilient connections between the other end of the lever and element, a yoke pivoted to the 5 intermediate portion of the lever, and means operatively connected to the yoke for operating the pressing element.

13. In a garment pressing machine having a movable pressing element, a lever fulcrumed on said element, spring connections 10 between said lever and element, a yoke pivoted to the lever between the fulcrum and spring, a toggle operatively connected to the yoke, and means for flexing the toggle for 15 moving the pressing element to and from its pressing positions.

14. In a garment pressing machine having a frame, a buck, and a press head movable into and out of pressing co-action with the 20 buck, a lever fulcrumed on the head, spring connections between the lever and press head, a yoke pivoted to the lever, a toggle having one of its links operatively connected to the yoke and its other link fulcrumed on 25 the frame, an additional toggle operatively connected to the first-named toggle to ap-

ply its force thereto in a direction at substantially right angles to a direct line between the frame fulcrum and the toggle joint of the first-named toggle in all positions of adjustment, and pedal-operated means for applying motive force to the second-named toggle in a direction at approximately right angles to a direct line between the ends of the additional toggle. 30

15. In a garment pressing machine, a frame, cooperative pressing elements, one of which is movable toward and from the other about a horizontal axis and provided with a rearwardly extending arm beyond said axis, 40 toggle members between the base of the frame and said arm, additional toggle connections between one of the toggle members and frame and having one of its connections provided with extra weight near its toggle joint, a pedal lever and connections between said pedal lever and the second-named toggle for operating the same. 45

In witness whereof I have hereunto set my hand this 27th day of December, 1926.

HERBERT G. BEEDE.
